UNITED STATES PATENT OFFICE.

ALBERT E. JOHNSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

MACHINE FOR PREPARING INSOLES.

1,384,804.

Specification of Letters Patent. Patented July 19, 1921.

Application filed November 30, 1914. Serial No. 874,718.

To all whom it may concern:

Be it known that I, ALBERT E. JOHNSON, a citizen of the United States, residing at Beverly, in the county of Essex and State of Massachusetts, have invented certain new and useful Improvements in Machines for Preparing Insoles; and I do hereby declare the following to be a full, clear, and exact description of the invention, such as will 5 enable others skilled in the art to which it appertains to make and use the same.

This invention relates to machines for preparing soles and more particularly to a machine for producing the type of insole 15 shown and described in my Patent No. 1,212,490 dated January 16, 1917.

Boots and shoes as commercially manufactured employ a counter or stiffening piece of sole leather in the back part of the 20 shoe within the upper to support the outer leather and prevent the shoe from "running over." In welt shoes the size and length of the counter is such that when lasting-in, it extends forward under the rear end of the 25 welt. Ordinarily the welt extends rearwardly to about the breast line of the insole and the counter extends forwardly a considerable distance beyond this line resulting in these two pieces overlapping each other 30 from $\frac{1}{2}$ of an inch to an inch and a half.

Welt insoles are generally fitted with an edge slit, forming a lip and feather, and with a parallel slit within the edge slit forming a channel and channel flap, the portion 35 between the two slits being the between-substance. These parts form the rib to which the upper and welt are stitched in the inseaming operation. It is customary for these cuts to be started and terminated at about the 40 breast line of the insole and after the insole is channeled so as to form these cuts, the lip, in men's work, is turned and laid over upon the between-substance. When the 45 outsole is laid, before the heel is secured to the shoe, there is at each side of the heel seat beneath the outsole for a short distance back of the breast line of the heel a substantial protuberance formed by the overlying 50 layers of the lip, counter and welt. This is disadvantageous in that it prevents nailing the heel on level and mars the appearance of the finished shoe at the shank. Further, in some types of insole channeling machines

difficulty is experienced in cutting in with the edge knife at the breast line in order to 55 produce the lip, and it has been the practice to run in and out across the heel seat, but such practice cuts into and weakens the heel seat which should be kept as strong as possible for the reception of the heel nails. 60

The object of the present invention is the provision of a machine for fitting or preparing sole blanks for use in boots and shoes in such a manner that whatever the parts used in the construction of the shoe may be, the 65 heel will be seated level and the shank will not be disfigured.

A further object of the invention is the provision of a machine whereby insole blanks may have a portion corresponding to 70 the feather gouged out of both sides of the shank adjacent the breast-line in order that the edge knife of a channel machine can be set in the insole at full depth of feather in starting the channeling operation and not 75 cut the insole in the heel seat.

To the accomplishment of these objects a feature of the invention contemplates the provision in a machine having a pair of sole gouging knives with a suitable table 80 which is adjustable to properly position soles of different sizes for the gouging cuts. The machine is equipped with means for simultaneously adjusting the gouging knives and table in order to properly locate the 85 gouges to be made in the sole. The table is movable relatively to the knives and has a set of markers thereon so that when the sole is brought up to the knives to be gouged the breast-line will be marked on the grain side 90 of the sole. After presenting the knives to the sole the table is advanced to feed the sole past the knives to lengthen the gouge the desired amount. The adjusting means for setting the knives and table are operated 95 by a common lever which works over a scale that indicates the different sizes of soles so that an adjustment of the lever upon the scale will adapt the knives and table for a size of sole corresponding to the size on the 100 scale.

The various features of the present invention will be best understood from an inspection of the accompanying drawings illustrating the best known mode of applying 105 its principle, in which:

Figure 1 is a side elevation of the machine showing the position of an insole while being gouged at the breast-line.

Fig. 2 is a front elevation of the machine.

Fig. 3 is a detailed elevational view showing the work table and mechanism for operating it.

Fig. 4 is a sectional elevation of the work table taken on the line 4—4 of Fig. 5, and

Fig. 5 is a section elevation of the work table taken on the line 5—5 of Fig. 4.

In the illustrated embodiment of the invention the column 4 carries a frame 6 which supports the insole gouging mechanism. Two vertical arms, 8 and 10 (Fig. 2) form a yoke and provide journals for the transverse shafts 12 and 14. The shafts 12 and 14 carry, respectively, the gouging knives 16—16 and the knife carriers 18—18, by which they are adjusted preparatory for gouging different sizes of insoles. These knives (see Figs. 1 and 2) are continuously rotated on shaft 12 by a belt 20 (indicated by dotted lines in Fig. 1) running around a fixed pulley 22, on the shaft 12, over the idler pulleys 24—24 mounted on the stud 26 in a yoke 28 and then around a power pulley at the base of the column 4. The yoke 28 is attached to the frame 6 and is adjustable toward and from the shaft 12 by means of the bolt and slot connections 30. The knives 16 are connected by a spline 32 (see Figs. 4 and 5) to the shaft 12 and rotate therewith but are free to move transversely on the shaft to permit a lateral adjustment for operating on different sizes and styles of insoles.

The gouging knives 16 are set to make a cut to the desired width of the feather on the channeled insole and when the insole is gouged by the knives the cuts are located on each side of the shank of the insole adjacent the breast-line. In order to locate the cuts at the edges of the shank of the various styles and sizes of insoles the knives should be adjustable to properly position them for each individual size of insole. To obtain this adjustment the knives are mounted in the carriers 18 which slide on the shafts 14 directly above the knife shaft 12. Shaft 14 is fastened against rotation by a set screw 34 (Fig. 2) and acts only as a slide for carriers 18. Each carrier consists of a block 36, slideable on the shaft 14, and a knife gage 38 and plate 40 secured thereto by means of bolts 42. Each gage and plate has an opening 44 at its lower end to receive the hub 46 of a knife 16 (see Fig. 14) and when they are attached to the block 36 the knife is held between them. The openings 44 for the reception of the knife hubs 46 are enough larger in diameter than the hubs to allow the gages 38 to be moved relatively to the knives in making an adjustment for depth

of gage. Each knife gage 38 is turned at right angles at its lower end and forms an abutment 48 (see Fig. 4) which extends laterally and outwardly past its corresponding plate 40. Each abutment has an opening 50 in its face through which the knife projects a distance equal to the depth of which it is desired to gouge the insole blank. To adjust a gage the locking bolts 42 are loosened and the slots 52 (see Fig. 1) in the gage 38 permits it to be raised and lowered by means of a thumb screw 53 (see Fig. 2). When the gages are set the bolts 42 are tightened to lock them in position. The front side of each carrier 18 is covered with a shield 54 (Fig. 1) held in place by means of a wing-nut 56. This shield covers the knives and protects the operative from injury while gouging insoles.

In adjusting the knives the carriers 18 are moved along the slide shaft 14 simultaneously toward and away from each other by the movement of a manually operated lever over a size scale. The movement of this size lever to a particular point on the scale 64 will position the knives for cutting a sole the size corresponding to that position. The size lever 58 is secured to a carrier cam shaft 60 by means of a split hub and bolt 62 so that in movement over the size scale 64 it rotates the shaft. The shaft 60 is journaled in a pair of brackets 66 which rise from the back of the frame 6 and project forwardly to meet the yoke arms 10 and 8. The bracket 66 to the left in Fig. 2 is integral with the arm 10 but the bracket on the right in this figure comes inside and abuts against the arm 8. The size scale 64 is mounted on a casting 68 which is secured to the bracket 66 by means of bolts 70. The casting 68 has a slot 72 through which the handle of the size lever 58 projects and the size lever handle has a spring pressed plunger 74 which registers with openings 75 on the scale 64 corresponding to the various sizes. Fixed on the shaft 60 by set screws 76 are a pair of segments 78 (see Fig. 1) having cam grooves 80 one for operating each carrier 18. Rollers 82 mounted upon studs 84 in the blocks 36 of the carrier work in the cam grooves. These cam grooves are formed in the segments 78 along intersecting inclined planes (see Fig. 2) so that when the shaft is rotated by the size lever 58 the carriers are moved toward and away from one another along the slides 14 to make the size adjustment of the knives.

The size lever 58, for adjusting the gouging knives for different sizes of soles, is also employed for adjusting the edge and heel gages mounted upon a work table in order to properly position an insole for the gouging operation. The insole edge gages 82 (Fig. 4) are attached one to each of the abutments 48 on the gages 38 so that ad-

justment of the knife carriers adjusts the edge gages. The edge gages 82 move insole supporting blocks 84 (Fig. 4) that have a row of pins 86 located upon their upper face 5 which act as a breast-line marker for insoles which are placed upon the table. The insole supporting blocks are mounted in T-shaped slots 88 in the table 90 and are connected for movement with the edge gages 82 by means 10 of an arm 92 on the edge gages which works in a yoke 94 on the end of the supporting blocks 84. With this structure, when the knives and edge gages are adjusted by the size lever the supporting blocks are carried 15 with the edge gages to accommodate the different widths of soles and give a support for the insole directly below the gouging knives.

In locating the gouges the insoles are 20 gaged from the heel and a heel gage cooperates with the edge gages to position the sole. All of these gages are adjusted simultaneously with the adjustment of the gouging knives. The heel gage 96 is mounted 25 upon a block 98 which slides in a guide-way 100 of the table 90. The heel gage is connected with the edge gage adjusting mechanism by means of a lever 102 (Fig. 1) centrally pivoted on a stud 104 carried by 30 one of the brackets 66. The upper end of the lever 102 carries roll 106 which works in a cam groove 108 in a bracket on the rear end of the size lever 58. The lower end of lever 102 is pivoted to a block 110 which 35 slides in the yoke 112 on the heel gage block 98. With this connection when the size lever 58 is moved to rotate the shaft 60 to adjust the gouging knives and end gages, the cam 108 acts to simultaneously rotate the lever 98 and thereby shift the heel gage along the 40 table 90.

In order to bring the knives and insole into cutting relation the table may be given a vertical movement by which the insole is 45 raised into contact with the gage abutments 48. To this end the table 90 is supported at its forward end by a toggle (Figs. 3, 4 and 5), the lower link 114 of which is pivoted to the yoke 116 on the machine frame and the 50 upper link 118 of which is pivoted to the table carrier 120. To the knuckle of the toggle there is pivoted the forward end of a pitman 122 which is provided at its rear end with an eccentric strap 124. The eccentric strap surrounds an eccentric 126 carried on a clutch shaft 128 journaled at the rear end of the frame in the bracket 65 60 65 66. The table carrier 120 and table 90 are pivoted on a bolt 130 held in a bracket 132 on the frame 6. The forward end of the table is connected to the carrier 120 by means of a bolt 134 which is pivoted in the table 90 at 136 and extends through a slot 138. The spring 140 mounted between the carrier and 65 table surrounding the bolt 134 tends to keep

the table in spaced relation to the carrier and is adjustable by a nut and pivot washer 142 on the bolt 134. The insoles to be gouged are positioned upon the table 90 between the edge gages 82 and against the heel 70 gage 96 and are brought up against the knives and abutment 48 when the toggle is straightened by rotation of the eccentric 126. The vertical movement of the toggle 75 for presenting insoles on the table to the gouging knives is constant so when the insole is forced against the abutments 48 the spring 140 provides for the different thickness of insoles. The spring 140 is strong enough to keep the insole pressed against 80 the abutment 48, and embed the marking pins 86 in the insole.

When the table carrier brings the insole up against the knives a gouge corresponding to the shape of the periphery of the knife 85 and of a depth corresponding to the projection of the knife below its gage is made but such a cut is not of sufficient length to take care of the extension of the counter beyond the breast-line of an insole in the 90 lasting operation so that it is necessary to give a relative movement to the insole and gouging knife to lengthen the cut the desired amount. For this purpose the table is 95 slidably mounted upon the carrier 120 between guides 144 (Figs. 3, 4 and 5) at the forward end of the carrier and the carrier pivots 146. The table 90 is slotted at its pivot 130 and the rear end thereof carries 100 the roll 148 which works in a cam groove 150 mounted upon the clutch shaft 128. The cam groove 150 is so related to the eccentric cam 126 that when the table is raised to present the insole the cam 150 moves the table past the knives and lengthens the gouge. 105 During the gouge lengthening movement of the table the heel gage 96 is held in a fixed position and slides in the groove 100 as the table 90 is moved forward. The insole is carried across the knives by means of the 110 pins 86 which grip the insole when the table is forced up. It will thus be seen that the pins 86 have the two-fold function of gripping the insole during the feeding movement and marking the breast-line. 115

The clutch shaft 128 which rotates the cams 126 and 150 is adapted to be connected with a driving pulley 152 connected with a source of power. The pulley 152 and shaft 128 are provided with a one revolution clutch 154. This clutch is the ordinary type of Horton clutch used generally in this class of machines and for this reason is only diagrammatically illustrated herein. When the treadle rod 156 is forced down it engages a latch 158 (see Figs. 1 and 2) and rotates it against the tension of the spring 160 out of the path of a stop 162 on the clutch plate. When the latch 158 is released the spring 164 will rotate the clutch plate 120 125 130 135 140 145 150 155 160 165 170 175 180 185 190 195 200 205 210 215 220 225 230 235 240 245 250 255 260 265 270 - and bring the shaft 128 into engagement with the pulley 152. After the shaft is started the treadle is released and the latch 158 swings back into the path of the stop 162 so that upon the completion of one revolution the stop engages the spring pressed plunger 161 and releases the clutch from the shaft 128. This plunger acts as a buffer to absorb the shock of releasing the clutch.
- 10 The adjustment of the size lever 58 over the scale 76 is arranged to take care of all sizes of insoles but only one width so that when the gages are set for one width the adjustment of the arm 58 on the scale will simultaneously set the gages and knives for all different sizes and that one width. In order to adapt the machine for different widths of insoles it requires a preliminary setting for each width. This preliminary setting is made by loosening the split hub connection 62 of the size arm 58 with the shaft 60, and if a special width in any size, say 7, is desired, the arm 58 is placed on the scale with the plunger 74 in the opening opposite the Fig. 7 and an insole of size 7 and the special width is placed upon the table against the heel gage 96 and the edge gages are brought into abutment with the edges of the insole by means of a hand-wheel 166 fast on the shaft 60. With the gages in this position the size lever is locked to the shaft 60 and its movement will now adjust the gages and knives for all sizes of insoles and this special width.
- 15 The operation of the machine is as follows: The preliminary adjustment of the size gages for the width of insole having been made as described above, the heel gage may be adjusted in order to properly locate the breast-line of the insole above the pins 86, by placing the marked insole of the size for which the machine is set upon the table between the edge gages so that the breast-line will rest upon the pins 86. The heel gage can then be properly adjusted against the end of the heel by means of set-screw 166 and this one adjustment of the heel gage is suitable for all sizes.
- 20 With the machine in the position shown in Fig. 1 the insole S is placed upon the table against the gages and the clutch treadle 156 is depressed to start the shaft 128 which forces the table up against continuously rotating knives by means of the cam 126 operating the toggle and then the cam 150 draws the sole across the knives to give the desired length of cut. After the insole is gouged the table is retracted by the cam 126 so that the gouged insole may be removed and the parts retracted ready for the next insole. The amount of movement of the table to vary the length of gouge can be changed by using different types of the cam 150.
- 25 While the above described machine is in-

tended primarily for gouging insoles before they have been channeled in order to provide a gouge to start the edge knife of the channeling machine in, it is equally well adaptable for gouging out a portion of the 70 lip after the insole has been channeled so as to properly prepare the insole for the lasting operation. Since the knives 24 are constructed to make a cut the width of the feather on the insole at the breast-line, the 75 same resultant product will be obtained whether the insole is gouged before or after channeling.

It should be distinctly understood, however, that while the machine of the present 80 invention is particularly adapted to produce an insole of the type disclosed in the Johnson Patent No. 1,212,490, hereinbefore referred to, it will be obvious to those skilled in the art that certain features of the invention are of broader application and may be employed in the manufacture of any type of sole. Accordingly, the invention is not limited to an operation upon an insole except as defined in the appended claims. 90

In the illustrated embodiment of the invention the table is moved both to present the sole to the fixed knives and to feed the sole past the knives in lengthening the gouge. Certain features of the present 95 invention, however, as defined by the claims, are not limited to such a construction but are broad enough to include a construction wherein a sole holding means, gouging knives and a table are used in which one 100 or two of them are movable relatively to the others or other.

The invention is not limited to the details of construction and operation herein described and illustrated nor to the conjoint 105 use of all its features, but it will be clear to those skilled in this class of machines and with the general objects of the present invention in view, changes may be made and the invention embodied in other forms within the terms and spirit of the claims. 110

Having thus described the invention, what is claimed as new is—

1. A machine for preparing soles, having, in combination, a sole support, gouging knives mounted adjacent the support to simultaneously operate on opposite margins of the sole, and means for moving the support to present a sole to the knives and draw the support past the knives to gouge out the 115 margin of the sole adjacent the breast line. 120

2. An insole preparing machine having, in combination, a support for a welt insole blank, means for positioning an insole upon the support, cutters relatively immovable toward and from the work supporting face of the support mounted opposite the support in position to gouge out a portion of the surface of the insole adjacent the breast line on each side of the shank between the edge and 130

the material of the between substance, and means to move the support toward the cutters to gouge the insole.

3. A sole preparing machine, having, in combination, a support for locating the heel portion of a sole, and rotary knives mounted on an axis substantially parallel with the face of the support and relatively immovable toward and from the work supporting face of the support, for gouging the margin of the sole adjacent the shank, and means for moving the support and knives relatively to one another to gouge the sole.

4. A machine for preparing insoles, having, in combination, a movable support for positioning an insole, a pair of rotary knives for gouging the insole adjacent the breast line on both sides of the shank to remove a portion of the insole corresponding in width to the feather, and means to move the support to present the insole to the knives.

5. A machine for preparing soles, having, in combination, a movable support for positioning a sole, adjustable rotary knives for gouging the sole, means for adjusting the knives to vary the position of the gouges in treating different sizes of soles, and means for moving the knives and support relatively to gouge the sole adjacent the breast line.

6. A sole preparing machine, having, in combination, a support for a sole, gouging knives adjacent the support for making narrow gouges in the opposite margins of the sole outside the material of the between substance and leaving the surface between the cuts intact, and means to move the support in two different directions, first toward the knives and then past the knives.

7. An insole preparing machine, having, in combination, a support for an insole, gages upon the support for positioning the insole, rotary knives arranged with relation to the positioning gages for making separated cuts in the margin of the insole to remove narrow portions of the surface adjacent the heel end of the insole, means for marking the insole, and means for relatively moving the support and knives to simultaneously mark and gouge the insole.

8. A sole preparing machine, having, in combination, a support for a sole, gages for the opposite edges and heel of the sole, means for simultaneously adjusting the gages to position a sole, and cutters adjacent the support for making separated cuts on the face of the sole adjacent the heel when the support and cutters are moved relatively to one another.

9. An insole preparing machine, having, in combination, a support for an insole, gages upon the support for positioning the insole, rotary cutting knives adjacent the support having their cutting edges arranged relatively to the gages to gouge out narrow por-

tions of the surface of the insole at the opposite sides adjacent the heel end, and means for moving the support to present an insole to the cutters.

10. A sole preparing machine, having, in combination, a support for soles, a cutter shaft, separated gouging knives mounted for rotation therewith and laterally movable thereon, laterally movable gages attached to the support adapted to embrace a sole placed thereon and position it for the cutting knives, and means for relatively moving the support and knives to one another to cut the sole.

11. A machine for preparing soles, having, in combination, a support for soles, a cutter shaft mounted above the support, gouging knives mounted on the shaft adapted to move laterally thereon, edge gages upon the support, size adjusting means connected with the knives and gages to simultaneously set the knives and gages for different sizes of soles, and means for moving the support and knives relatively to one another to gouge a sole.

12. A machine for preparing soles, having in combination, a support for a sole, sole edge and heel gages mounted upon the support, rotary knives mounted above the support, size actuating mechanism connected with the gages and knives to simultaneously set the gages and knives to position different sizes of soles, and means to relatively move the support and knives to gouge a sole.

13. A sole preparing machine, having, in combination, a support for a sole, gages mounted upon the support for positioning the sole, gouging knives adjacent the support for gouging the sole, size adjusting mechanism for positioning the knives and gages for different sizes of soles, means for setting the knives and gages for different widths of soles, and means to relatively actuate the support and knives to gouge a sole.

14. A machine for preparing soles, having, in combination, a support for a sole, sole edge and heel gages upon the support for positioning the sole, rotary gouging knives mounted above the support for gouging the sole, means for raising the table to present the sole to the knives, and means for moving the table with the sole thereon to lengthen the gouging cut of the knives.

15. An insole preparing machine, having, in combination, an insole support having gages thereon to position an insole, an identification marker located upon the support, insole lip gouging knives above the support, and means for raising the support to present the insole to the knives and simultaneously mark the insole.

16. A machine for preparing soles, having, in combination, a support for positioning a sole, rotary knives adjacent the support, means to move the support to present

the sole to the knives, and means upon the support to provide for the accommodation of different thicknesses of soles.

17. A sole preparing machine, having, in combination, a sole support, gouging knives mounted in carriers above the support, means for adjusting the carriers and knives toward and away from one another for different sizes of soles, gages upon the carriers for determining the depth of the gouge, and means to relatively move the knives and support to gouge a sole.

18. A sole preparing machine, having, in combination, a support for positioning a sole, a rotary shaft mounted above the support, rotatable knives mounted upon the shaft for lateral movement thereon, carriers slidably mounted above the shaft for moving the knives, and means for adjusting the carriers to position the knives.

19. A sole preparing machine, having, in combination, a support for positioning a sole, a rotary shaft above the support, gouging knives mounted for lateral movement upon the shaft, carriers embracing the knives slidably mounted above the shaft, edge gages attached to the carriers, and size adjusting means for simultaneously adjusting the edge gages and gouging knives for different sizes of soles.

20. A machine for preparing soles, having, in combination, a support for positioning a sole, a shaft above the support, rotatable gouging knives upon the shaft, carriers embracing the knives slidably mounted above the shaft, and a knife gage mounted upon each carrier and movable relatively to its knife for gaging the depth of the gouge.

21. A sole preparing machine, having, in combination, a support for positioning a sole, a breast line marker on the support, rotary sole cutting knives above the support, and means for relatively moving the knives and support to simultaneously gouge the sole and mark the breast line thereon.

22. A sole preparing machine, having, in combination, a support to position a sole, rotary gouging knives above and at each side of the support, means for relatively moving the knives and support to gouge the sole, and mechanism for moving the support

in a direction normal to the axes of the knives to lengthen the gouge.

23. An insole preparing machine, having, in combination, a support for positioning an insole, rotary knives for gouging the insole, a breast line marker on the support, and means for relatively moving the support and knives to present the insole to the knives, grip the insole and transfer the point of cut of the knives along the insole to lengthen the gouge.

24. A machine for preparing soles having, in combination, a sole support, cutters for forming recesses in opposite sides of a sole placed on the support, automatic means for yieldingly actuating the support to position the sole in yielding engagement with the cutters, and means for relatively actuating the support and cutters to move relatively the cutters and sole past each other.

25. A welt insole preparing machine having, in combination, means for supporting a welt insole; shank cutting means; and means for relatively moving the supporting and cutting means to produce an elongated unlipped shank recess in the marginal portion of the insole, adjacent to the breast line and abutting the between-substance, of such depth and width as to be capable of receiving the overlying portions of the counter and welt forward of the breast line.

26. A welt insole preparing machine having, in combination, means for supporting a welt insole; shank cutting means opposite the insole for entering its surface to produce an unlipped shank recess of uniform depth throughout its width, the inner edge of which abuts the between-substance; means for elongating said recess by relatively moving the support and cutting means past each other, said means operating to stop said elongating process when the elongation is sufficient to receive the overlying portions of the counter and welt forward of the breast line; and means to cause removal of said cutting means from the recess.
